UNITED STATES PATENT OFFICE.

ISIDOR GARLIN, OF BROOKLYN, NEW YORK, ASSIGNOR TO SILBERMANN, KOHN & WALLENSTEIN, INC., OF NEW YORK, N. Y., A CORPORATION OF NEW YORK.

DESIGN FOR A FINGER RING.

Application filed February 1, 1926. Serial No. 16,360. Term of patent 3½ years.

To all whom it may concern:

Be it known that I, ISIDOR GARLIN, a citizen of the United States of America, residing at Brooklyn, county of Kings, State of New York, have invented a new, original, and ornamental Design for Finger Rings, of which the following is a specification, reference being had to the accompanying drawings, forming part thereof.

Fig. 1 is a side elevation of a ring embodying the new design;

Fig. 2 is a top plan view thereof; and Fig. 3 is an edge view thereof.

I claim:

The ornamental design for a finger ring as shown.

In witness whereof I have signed this specification this 30th day of January, 1926.

ISIDOR GARLIN.
